UNITED STATES PATENT OFFICE

135,288

DESIGN FOR A PICTURE FRAME

Hilda E. Perkins, Binghamton, N. Y.

Application January 26, 1943, Serial No. 109,348

Term of patent 7 years

To all whom it may concern:

Be it known that I, Hilda E. Perkins, a citizen of the United States of America and a resident of Binghamton, county of Broome, and State of New York, have invented a new, original, and ornamental Design for a Picture Frame, of which the following is a specification, reference being had to the accompanying drawing, forming part thereof, wherein—

I claim:

The ornamental design for a picture frame, substantially as shown.

HILDA E. PERKINS.
